UNITED STATES PATENT OFFICE.

JOHN W. BEASLEY, JR., OF LOS ANGELES, CALIFORNIA.

GARMENT SUPPORTER.

Application filed April 23, 1920. Serial No. 376,085.

To all whom it may concern:

Be it known that I, JOHN W. BEASLEY, Jr., a citizen of the United States, residing at Los Angeles, in the county of Los Angeles and State of California, have invented certain new and useful Improvements in a Garment Supporter; and I do hereby declare the following to be a full, clear, and exact description of the invention, such as will enable others skilled in the art to which it appertains to make and use the same.

The object of the invention is to provide a simple and efficient garment supporting or holding device of the elastic or contractile type wherein the disadvantages of rubber and like materials are avoided and wherein the application of the supporter or holder to the garment is facilitated, particularly when the device is intended to be used in connection with a sheath or pocket in the garment as in connection with waist bands, stocking tops and the like, and with this object in view the invention consists in a construction and combination of parts of which a preferred embodiment is shown in the drawing, wherein

Figure 1 is a view of the supporter or holder applied in the operative position to a garment, a portion of the latter being broken away.

Figure 2 is a view of the supporter detached.

Figure 3 is a sectional view showing the relation between the attachable or engageable extremities of the supporter or holder.

The device consists essentially of a body portion 10 composed of a coil of fine wire having a contractile strength of the required degree to suit the function which it is to perform, said body portion being provided at its extremities respectively with the complementary members 11 and 12 of a fastening means which in the construction illustrated consists of a pin and a terminally reduced socket for the reception of the pin and wherein the latter is provided with a bore for frictionally engaging and holding the pin when the members are united. The socket forms a sheath for the pin, to prevent contact of the extremity of the latter with adjacent objects, and at their inner ends said pin and socket are provided with heads 13 and 14 to which the ends of the body coil are substantially secured.

The supporter may be threaded into a sheath or pocket formed on or constitut-

ing a part of a garment such as that illustrated at 16 in the drawing, and the reduced socket member 12 constitutes a suitable threading head for facilitating the introduction of the device into the pocket, it being the intention to remove the supporter or holder from the garment when the latter is to be laundered, so that it is not exposed to the deteriorating effect of the water which serves in a very short time to render the ordinary rubber supporter useless.

The socket member 12 comprises a hollow casing or shell 17 provided with end openings extending into the interior thereof, the inner walls of the casing or shell incline from the inner to the outer end thereof to vary the inside diameter of the shell and the inner end of the shell or casing is provided with an annular wall surrounding the inner end opening of the casing. The head 14 is provided with a spherical portion 18 from the forward end of which projects the tubular member 19 provided with a shoulder 20 and a head 21 which receives balls 22. An expansible coil spring 23 is arranged within the casing or shell 17 and surrounds the tubular member 19 and bears against the inner wall of the shell and the shoulder 20 and serves to force the shell onto the member 19 and to cause the balls 22 to recede into the head 21. In operation the head 13 and the spherical member 18 are engaged between the fingers and thumb of the hand, and the pin is inserted into the casing 17 and enters the tubular member 18 and forces the balls 22 from the head 21 and causes the same to engage and bind against the inner walls of the casing or shell. Independent movement of the shell or casing with respect to the remainder of the structure will release or more firmly bind the pin in the socket, according to the direction of movement of said shell. The action of the spring 23 is such as tends to bind the pin in the socket.

While other forms of terminal fastening means for the body portion of the supporter may be employed the advantages of that herein disclosed will be apparent particularly in the matter of facilitating the attachment to and removal from the garment in connection with which the same may be used.

Having thus described my invention, what I claim is:

A fastener of the class described compris-

ing a flexible body, a head secured to one end thereof, a rigid pin extending forwardly from said head, a head secured to the opposite end of the body, a socket member carried by said second named head, said socket member comprising a tubular member rigidly secured to said second named head and projecting forwardly therefrom and adapted to receive said pin, a shell having an opening in one end and a shoulder surrounding said opening, said tubular member projecting into said shell through said opening, said tubular member having a head forming a shoulder at its free end, balls arranged in radially extending openings in said head, said shell having tapering inner walls adapted when the shell is moved to engage and move said balls inwardly of

said head to engage said rigid pin to secure it within said tubular member, a coil spring within said shell and surrounding said tubular member and having one of its ends engaging said head and having its other end engaging said shoulder and normally maintaining said shell in the position described, and said shell adapted to move independent of movement of the flexible body and in opposition to the action of said coil spring to release the rigid pin from the tubular member.

In testimony whereof I affix my signature in presence of two witnesses.

JOHN W. BEASLEY, JR.
